HYDRAULIC APPARATUS

Cecil E. Adams, Columbus, and Wendell E. Renick,
 Grove City, Ohio, assignors to The Denison
 Engineering Company, Columbus, Ohio

Application December 16, 1947, Serial No. 791,946

13 Claims. (Cl. 60—97)

1

This invention relates generally to hydraulic apparatus and in its more particular aspects relates to presses. Still more particularly, the invention pertains to presses with attachments in the form of movable work supports operative to successively position work-receiving stations in registration with the press ram.

One of the objects of this invention is to provide a hydraulic press with a reciprocating table and a hydraulic system by which the press ram and table are automatically operated to alternately position work-receiving stations on the table in registration with the ram and then perform a cycle of ram movement consisting of pressing and return strokes.

Another object of the invention is to provide a hydraulic press with a reciprocating table and a hydraulic system embodying a plurality of automatic control valve mechanisms which are interrelated so that the valve mechanism for controlling the press ram will permit but a single operation of the ram and then direct fluid pressure to the control mechanism for the table to cause movement of the table, the latter control mechanism having an element operated by the table when it reaches a predetermined position to apply fluid pressure to a part of the ram control mechanism to initiate a cycle of operation of the ram, the initial movement of the ram interrupting further flow of fluid to the table control mechanism until the cycle of ram movement has been completed. In this manner, all danger of interference between ram and table or apparatus carried thereby will be avoided.

A further object of the invention is to provide a press with a reciprocating table and a hydraulic system for operating the press and table in a certain sequence, the system embodying a table control valve including a casing and a plurality of spool elements certain of which are responsive to fluid pressure to effect the operation thereof and at least one of which is responsive to table motion to select the direction of the next succeeding table movement.

A still further object of the invention is to provide a press with a sliding table and a hydraulic system including a ram control valve having a fluid pressure responsive element for initiating a cycle of operation of the ram and a table control valve having a plurality of spool elements one of which is operated by the table at the termination of movement in either direction to apply fluid pressure to the pressure responsive element in the ram control valve to initiate a cycle of movement of the ram, another spool element in the table

2

control valve being responsive to fluid pressure to move to a position to direct the entire available pressure supply to the pressure responsive element of the ram control valve to retain the same in position to continue the pressing stroke of the ram until another source of fluid pressure for performing this function becomes available.

Further objects and advantages of the present invention will be apparent from the following description, reference being had to the accompanying drawings wherein a preferred form of embodiment of the invention is clearly shown.

In the drawings:

Figure 1 is a perspective view of a press formed in accordance with the present invention, this press being provided with a reciprocating table.

Figure 2 is a front elevational view of the press shown in Fig. 1.

Figure 3 is a side elevational view of such press, Figures 4 and 5 are detail longitudinal sectional views taken through the reciprocating table on the planes indicated by lines IV—IV and V—V respectively of Figure 3.

Figure 5A is a vertical transverse sectional view taken through the table on the plane indicated by the line VA—VA of Fig. 4.

Figure 6 is a diagrammatic view of the hydraulic system and operating mechanism contained therein by which the press and sliding table are operated, the mechanism of the system being shown in the positions occupied when the press is idle;

Figures 7 to 10 are diagrammatic views of the portion of the hydraulic system employed to operate the table showing the mechanism thereof in various stages of table operation, and

Figure 11 is a detail sectional view showing the power cylinder for moving the table and the table control valve mechanism.

Referring more particularly to the drawings and especially Figures 1 to 3, inclusive, the press forming the subject matter of the invention is more generally shown therein. This press comprises a frame 10 having base, column and head sections 11, 12, and 13 respectively, and a work-supporting table designated generally by the numeral 14. This work-supporting table is carried by the forward portion of the base section 11 beneath the forward portion of the head section 13. This head section of the press contains a power cylinder 15 in which a ram 16 is received for sliding movement, the ram projecting downwardly from the head section toward the table. In operation the ram moves toward and away from the table through the operation of the power cylinder.

The press 10 is provided with a fluid reservoir 17, a power-operated pump 18, and a hydraulic system 20 for utilizing the fluid pressure generated by the pump 18. The press is similar in construction and operation to that shown in co-pending applications Serial Nos. 589,163, filed April 19, 1945, (now Patent No. 2,491,355 issued Dec. 13, 1949) and 682,974, filed July 11, 1946. The press per se includes a control valve mechanism, designated generally by the numeral 21, used for controlling the operation of the power cylinder 15, both the control valve mechanism and power cylinder being arranged in the hydraulic system 20. The mechanism 21 is also disposed in the head section of the press frame and is provided with an exteriorly arranged operating handle 22; this handle may be employed to cause either a single cycle of operation of the press and sliding table or an automatically repeated series of such cycles. It may also be used to interrupt a cycle of operation when occasion demands.

The movement of handle 22 imparts rotary movement to a disk 23 journaled in the control valve mechanism. This disk carries an eccentrically arranged pin 24 which projects into a bore 25 in the body 26 of the control valve mechanism, the bore 25 receiving a slidable valve spool 27. The pin 24 extends into a slot formed in the lower portion of the spool 27 and, due to the eccentric arrangement of the pin, longitudinal movement of the spool will result when the disk 23 is rotated. Spool 27 is normally urged toward a centered position in which it is shown in Figure 6 by coil springs 28 and 30, disposed between the opposite ends of the spool and the bottom and top covers 31 and 32 of the valve body 26. Spool 27 has a reduced intermediate portion 33, the purpose of which will appear as the description proceeds. Body 26 is also provided with a second bore 34 disposed in parallel relationship to the bore 25, the body having a plurality of longitudinally spaced annular grooves 35 to 42, inclusive, extending around the bores 25 and 34, certain of the grooves communicating with bore 25 and the others communicating with bore 34.

Bore 34 also receives a valve spool 43 which is of generally tubular formation and is provided with longitudinally spaced sets of laterally extending ports 44 to 51, inclusive. Spool 43 receives a second spool 52 which is provided with reduced portions 53, 54, 55 for the purpose of establishing communication between certain sets of the ports in spool 43. Spool 52 is normally urged toward the lower end of the chamber in spool 43 by a coil spring 56 disposed in a socket in spool 52 and engaging a cap 57 employed to close the upper end of spool 43. Spool 52 includes a longitudinal passage 58 extending from the spring socket to the lower end of the spool, this passage being intersected adjacent the lower end of the spool by one or more transversely extending passages 59. The spool 43 has a downwardly extending rod 61 which projects through the lower cap 31 of the valve body and extends toward the base section in a recess in the front wall of the column section 12. This rod 61, which is commonly termed a shipper rod, is provided with one or more collars 62 for engagement by a rearwardly extending arm 63 carried by the press ram 16. When the ram is moving in an upward direction and it engages one of the collars 62, it will move the spool 43 upward to the position shown in Figure 6. Normally this spool occupies a slightly lower position in which a shoulder 63A thereon coincides with the upper surface of a washer 64

which in turn is yieldably held in engagement with a shoulder 65 in the valve body 26 by a coil spring 66, this coil spring also engaging a collar 67 surrounding the shipper rod 61. The collar 67 engages a transversely extending pin 68 in the shipper rod and when the shipper rod moves in an upward direction the pin 68 forces the collar 67 against the spring 66 compressing the same against the washer 64, the spring 66 thus yieldably resists upward movement of the spool 43. It will be obvious that initial downward movement of the ram 16 will move the arm 63 away from the collar 62 permitting spring 66 to expand and move the shipper rod and the spool 43 downward until collar 67 engages the lower end of a socket in the cap 31. When the parts of the control valve mechanism 21 are disposed as shown in Figure 6, the press will be idle and the fluid discharged by pump 18 will be directed to the reservoir 17, the fluid flowing first to groove 35 through conduit 69 and from groove 35 to the interior of spool 43 through ports 49 and outwardly therefrom through ports 48 to groove 38, which groove communicates with a recess 70 which in turn communicates with bore 25. The fluid will flow upwardly in bore 25 around the reduced portion of spool 27 to the groove 42, this groove communicating with groove 37. The fluid then flows through ports 50 in spool 43 to the interior thereof above spool 52 and outwardly through ports 51 to groove 40. This groove communicates with the upper end of bore 25 which in turn is directly connected with the reservoir 17. When fluid is discharged in this manner, pump 18 will operate under a minimum load.

Valve mechanism 21 constitutes, in effect, a master valve in that it controls the operation of the entire hydraulic system 20, all fluid flowing from pump 18 passing through this valve before being utilized either in the operation of the power cylinder 15 or the reciprocating table 14. The upper and lower ends of power cylinder 15 are connected by lines 71 and 72 with grooves 37 and 36, respectively; these lines constitute alternate inlet and exhaust lines depending upon the direction of movement of the piston 73 in the power cylinder 15. The hydraulic system 20 includes another line 74 which extends from recess 70 in valve body 26 to the control valve mechanism indicated generally by the numeral 75—A for the reciprocating table 14. Valve mechanism 75—A includes a valve body 76—A which, for convenience in illustrating, has been shown in various figures of the drawing as composed of three separate pieces. It should be obvious that this valve could be of one piece or more depending upon the desires of the manufacturer. Valve body 76—A includes a plurality of bores 75, 76 and 77 for the reception of spools 78, 80 and 81, the first spool 78 being disposed for sliding movement in bore 75, spool 80 being disposed in bore 76 and spool 81 in bore 77. Line 74 extends to an inlet port 82 which in turn is connected with a groove 83 surrounding bore 75. Spool 78 is provided with an external groove 84 which, when the spool is disposed in the position shown in Figure 6, establishes communication between groove 83 and a port 85 connecting with bore 75 in longitudinally spaced relation from groove 83. Spool 78 is normally urged to this position by a coil spring 86 disposed between the spool and one end of bore 75.

Port 85 is connected by a passage 87 with a pair of grooves 88 and 90 formed in the body 76—A around the bore 76, these grooves being spaced

longitudinally of such bore. Grooves 88 and 89 are connected in turn by passages 91 and 92 with additional grooves 93 and 94 formed in the body around bore 77. Spool 81 is formed with a plurality of longitudinally spaced, annular grooves 95, 96, and 97, groove 95 serving, when spool 81 is positioned as shown in Figure 6, to establish communication between groove 93 and another groove 88 disposed in body 76—A adjacent groove 93. Groove 98 is connected by a passage 100 with a groove 101 formed adjacent the left end of bore 76. When fluid is supplied to line 14 and spools 78, 80 and 81 are disposed as shown in Figure 6, fluid will be conducted from line 14 through passage 87, groove 88, passage 91, grooves 93, 95 and 98, and passage 100 to groove 101 and the left end of bore 76. This fluid will exert a force on spool 80 moving the same to the right to the position shown in Figure 7. When spool 80 occupies this new position, a groove 102 in the exterior thereof will establish communication between groove 88 and groove 103 located adjacent thereto, so that fluid introduced to groove 88 will flow to groove 103 and from this groove through passage 104 to another groove 105 surrounding bore 77. This groove 105 is connected by line 106 with the outer end of a hollow piston rod 107 which forms a part of a piston and cylinder type fluid motor 108 employed to move the table 14. In this instance the cylinder 110 of motor 108 is directly connected with the movable portion 111 of the table while the piston 112 of such motor and the piston rods 107 and 113 are held stationary. It will be seen that when the piston and piston rods are stationarily held, fluid pressure supplied to the cylinder at one or the other end of the piston will react to impart movement to the cylinder and, in this instance, the table section 111 connected thereto.

This table section 111 is supported for horizontal sliding movement in a trough-like member 114 which is mounted on the forward portion of the base section of the press frame. It is guided by vertical flanges 115 projecting upwardly from the member 114. Inwardly projecting strips 116 secured to the upper edges of the flanges 115 prevent the displacement of the table. As shown in Figure 4, the piston rods 107 and 113 are secured to upwardly projecting lugs 117 formed on the member 114; these rods project into the cylinder 110 and engage opposite ends of the piston 112. The inner end portions of the rods 107 and 113 are provided with a series of holes 118 through which fluid flows from the rods into the cylinder. A plurality of openings are provided in longitudinally spaced relationship so that, as the table approaches the end of its stroke, the openings will be covered consecutively, thus gradually reducing the discharge of fluid from the end of the chamber toward which the piston is travelling, and the speed of movement of the table. The table will thus start and stop gradually rather than suddenly. When fluid is supplied to one end of the power cylinder in the manner illustrated by the arrows in Figure 7, the table will move, in this instance, toward the left, causing fluid at the right hand end of the piston 112 to be discharged through the openings in piston rod 113 to the interior thereof. This oil will flow through line 120 to groove 121 which surrounds bore 77 and from this groove through passage 122 to groove 123 surrounding bore 76. Groove 123 is at this time, connected with groove 124 also surrounding bore 76 by an external groove 125 formed in spool 80. From groove 124

fluid is conducted by conduit 126, to the reservoir 17. It will be seen that, as long as fluid under pressure is supplied to cylinder 110 and exhausted therefrom in this manner, table 111 will continue to move toward the left. The movable portion of table 111 is provided with a yoke member 127 having right and left ends 128 and 130. These ends project laterally into registration with the spool 81 and are so arranged that in the final stage of movement of the table they will move the spool 81 to the right or left depending upon the direction of movement of the table.

Figure 8 illustrates the hydraulic system after the table has moved to the left and the laterally projecting end 128 of the yoke has moved spool 81 to the left. At this time the reduced portion or groove 96 establishes communication between groove 105 and groove 131 which groove is disposed between groove 105 and groove 121, these grooves all surrounding bore 77. Groove 131 is connected by a passage 132 with one end of bore 75 at the end of spool 78. This spool is reduced slightly at this end so that fluid entering from passage 132 may react on the spool to move the same to the end of bore 75 in opposition to the force of spring 86. Spool 78 has been illustrated in this position in Figure 8. When in this position passages formed in the spool will establish communication between port 82 and the end of the bore 75 communicating with passage 132 and fluid supplied to the control valve mechanism 75—A through line 14 will be immediately directed through a control port 133—A into line 133 without flowing to the table motor 108.

Line 133 extends from valve mechanism 75—A to groove 39 in valve body 26. When the spool 43 is in the position occupied when the ram is elevated as shown in Figure 6, ports 44 will be in communication with groove 39 and fluid flowing through line 133 will be directed to groove 39 and through ports 44 to the interior of spool 43 at the lower end of spool 52. This fluid will exert a force on spool 52, to move the same upward in opposition to the spring 56. When the spool 52 occupies its uppermost position the reduced portion 54 will establish communication between ports 49 and ports 50 and fluid supplied to the groove 35 through line 69 will then be directed through ports 50 to groove 37 from which it will flow through line 71 to the upper end of power cylinder 15; this fluid will exert a downward force on the piston 73 causing the same to move in a downward direction. In so moving, the piston 73 will displace fluid from the lower portion of the power cylinder 15 through line 72 to groove 36. This fluid will flow through ports 46 into passages 60, which will then be in registration with such ports, and through the longitudinal passage in the spool 52 to the upper end of the chamber in spool 43; this fluid will be exhausted through ports 51 to groove 40 from which it will flow to reservoir 17. Due to the resistance to fluid flow offered by relatively small longitudinal passage 58 in the spool 52 a back pressure will be created which will be transmitted to the fluid in the spool 43 at the lower end of the spool 52, this back pressure will maintain spool 52 in its elevated position as long as piston 73 is moving in a downward direction.

It will be noted that upon initial downward movement of the piston, spool 43 will be moved downward a slight distance by spring 66 until ports 48 no longer register with grooves 38. When this registration has been destroyed fluid from

the power source will no longer be supplied to line 74 and valve mechanism 75-A. Inasmuch as fluid is no longer supplied to this mechanism there will be no force tending to move table 14. All the fluid from the power source will then be available to move piston 73 and ram 16 in a downward direction. When the ram engages an obstruction which offers sufficient resistance to cause the pressure in the upper end of the cylinder 15 and the portion of the hydraulic system between the power cylinder and the pump 18 to increase to a previously set value at which fluid will be discharged through a line 134 and relief valve 135, the piston 73 will cease to move in a downward direction. When this piston stops moving, the back pressure in the lower portion of cylinder 15, line 72, groove 88, passage 60 and the lower portion of the chamber in spool 43 will fall permitting spool 82 to be moved in a downward direction to a position establishing communication between ports 49 and 47 in spool 43. Ports 47 will at this time be in registration with groove 36 and fluid supplied thereto will be directed through conduit 72 to the lower end of the power cylinder 15. The force of this fluid will move piston 73 in an upward direction causing a return movement of piston 73 which will displace fluid from the upper end of power cylinder 15 through line 71 to groove 37, this fluid flowing through ports 50 to the interior of spool 43 above spool 52, such fluid flowing outwardly through ports 51 to groove 40. This fluid will flow over the path previously mentioned to reservoir 17.

At this time ram 16 and piston 73 will be moving in an upward direction and in the final stage of movement will, through the arm 63, move shipper rod 61 and spool 43 back to the position illustrated in Figure 6, wherein ports 48 will register with groove 38. As the spool 43 is so moved, communication between ports 47 and groove 36 will be interrupted and fluid will no longer be supplied to the lower end of the power cylinder 15. The ram 16 will then discontinue moving and be retained in an elevated position. The full pump supply will again be available for the operation of the sliding table.

From Figures 6 to 10, inclusive, it will be observed that the body 76-A is provided at the ends of the bore 76 with cap members in which reduced cylinders 136 are formed for the slideable reception of small pistons 137. These pistons have shoulders 133 to limit their inward movement, and reduced extensions which project into the interior of the bore and engage the ends of spool 80. When spool 81 is moved from one extreme position to the other by the final stage of movement of the reciprocating table and fluid pressure is supplied directly to passage 132, this fluid pressure will be applied through passages 139 and 140 to the outer ends of pistons 137, these pistons will be urged inwardly causing the spool 80 to be moved to a centered position in the bore 76. Spool 80 has a reduced longitudinally extending passage 141 to permit this longitudinal movement, fluid flowing from one end of the bore through the passage 141 to the opposite end. This centering of spool 80 takes place immediately after spool 81 has been moved by the table. This movement is important inasmuch as it assists in determining the direction of movement of the table 111 after the ram has completed its return stroke and fluid is again supplied from the pressure source to line 74. This fluid will flow to port 82 in the body 76-A. The system will then be in condition for the return move-

ment of the table, spool 78 having returned to its normal position when the back pressure was dissipated due to the stoppage of the ram at the termination of its power stroke. Fluid thus supplied to port 82 will again be directed through passage 87 to grooves 88 and 90. Upon the initial flow of fluid through line 74 the parts of the table control valve mechanism 75-A will be caused to assume the positions shown in Figure 10, spool 80, being moved to the left by fluid pressure flowing from port 82 through line 87 to groove 90, through passage 82 to groove 94, through groove 97 in spool 81 to groove 143 and through passage 144 to the right hand end of bore 76. When fluid was first supplied to line 74 after ram 16 had been fully retracted, spool 80 occupied a centered position as shown in Figure 9; fluid supplied to line 74, however, followed the path outlined above to the right hand end of bore 76 and moved the spool 80 to the left to the position shown in Figure 10. When this spool occupies this position, a groove 145 therein establishes communication between groove 90 and groove 123, which is connected by passage 122, groove 121, and passage 120 with the outer end of piston rod 113. Fluid supplied to piston rod 113 will flow into the right hand end of cylinder 110 causing the cylinder and the table 111 connected therewith to move toward the right. When so moving, fluid will be dispelled from the left hand end of cylinder 110 through the piston rod 107, line 106, groove 105, passage 104, grooves 103 and 125 to groove 124 from which it will flow through line 126 to reservoir 17. When the table approaches the limit of its movement toward the right, end 130 of yoke 127 will again shift spool 81 to the right to cause the groove 96 thereon to connect grooves 121 and 131 so that fluid under pressure supplied to the valve mechanism 75-A will be directed through passage 132 to the left hand end of bore 75 to again move spool 78 to the right in opposition to the spring 86. When so moved spool 78 or passages formed therein will again establish communication between line 78 and line 133 so that fluid pressure may be applied to the spool valve 52 to initiate a cycle of operation of the ram.

As previously mentioned, when line 132 is supplied directly with fluid pressure, such fluid pressure will be applied through lines 139 and 140 to the outer ends of pistons 137 to effect a centering of the spool 80. It will be obvious from Figures 7, 8 and 10 that when spool 80 occupies either the right or left extremity of movement only one of the pistons 137 will be active to move the spool. It will also be obvious that after the spool has reached the centered position further movement will be prevented by the piston at the opposite end of the bore.

From the foregoing it will be apparent that the system, which has been shown complete in Figure 6, will operate to effect movement of the reciprocating table to one extreme position, cause a cycle of operation of the ram including power and return strokes, then effect another movement of the table in the opposite direction, the movements of the table and ram being performed in sequence. Through the provision of the centering mechanism for the spool 80 and the movement of the spool 81 by the table, the direction of each succeeding table movement will be determined. In the event the power should be interrupted causing the press to cease operation at any particular stage other than at the beginning 78 of a cycle of movement, the cycle being per-

11

fluid supplied to said body to said table motor to move said table in one direction; means actuated by said table adjacent the termination of movement in either direction to move one of said spool members to a new position to direct the fluid to said first-mentioned valve mechanism and apply the same to said flow-directing element to initiate an operation of said ram, certain of said spool members being responsive, when said one spool is in said new position, to fluid pressure to move to another position to cause the succeeding table operation at the termination of the ram cycle.

7. A hydraulic control valve comprising a body, provided with an inlet port, a pair of motor ports, a control port and an exhaust port, said body also having a plurality of bores; a first spool member disposed in one of said bores for sliding movement, said first spool serving in one position to interrupt communication between said inlet and said control port and to establish such communication in another position thereof; second and third spool members arranged for sliding movement in two other bores in said body, said second spool member having actuating extremities extending to the exterior of said body to be actuated by extraneous means, said second and third spools being slidable between two extremities of movement; means engaging said third spool, said means being operative to move the spool to a position intermediate the two extremities of movement thereof, said second spool member serving when in either extreme position to utilize fluid pressure supplied to said inlet port to move said third spool member to an extreme position to establish communication between one motor port and said inlet and the other motor port and said exhaust, movement of said second spool member to the opposite extreme position serving to connect the motor port communicating with said inlet with said control port, said position of said second spool also serving to render the third spool-engaging means operative.

8. Hydraulic control valve mechanism comprising a body provided with an inlet, a pair of cylinder ports, a control port and an exhaust port, said body also having a plurality of bores; a plurality of spool members disposed for sliding movement in said bores, the first of said spool members having actuating extremities extending to the exterior of said body, a second spool serving in either of two positions to connect one of said cylinder ports to said inlet port and the other to said exhaust port; means yieldably urging a third spool toward one position, said third spool being responsive to fluid pressure to move to a position connecting said inlet and said control port; and means operative when said first spool is shifted to cause said second spool to move to a position intermediate said two positions.

9. A hydraulic control valve comprising a body provided with an inlet port, a pair of motor ports, a control port and an exhaust port, said body also having a plurality of bores; a first spool member disposed for sliding movement in one of said bores; means yieldably maintaining said first spool member in position to obstruct communication between said inlet and control ports, said first spool being responsive to fluid pressure to move to a position establishing such communication; second and third spool members arranged for sliding movement in two other bores in said body, said second spool member having actuating extremities extending to the exterior of said

12

body to be operated by extraneous means, said second and third spools being movable between two extreme positions of longitudinal movement; means engaging said third spool, said means being operative to move said third spool to a position intermediate said extreme positions when fluid pressure is applied to said first spool to move the same to a position establishing communication between said inlet and said control port.

10. In a hydraulic system, a source of fluid pressure; a reversible fluid motor; control valve mechanism between said fluid pressure source and said motor, said mechanism having relatively movable valve elements operative in one relative position to direct fluid from said source to said motor to cause forward operation thereof and in a second relative position to cause reverse operation of the motor; a second reversible fluid motor; a second control valve mechanism operative to alternately cause forward and reverse operation of said second fluid motor; means actuated by said first fluid motor adjacent the termination of reverse operation for placing the relatively movable valve elements of the first-mentioned control mechanism in a third relative position wherein flow from said source to the first-mentioned fluid motor is interrupted and flow to the second control valve mechanism established; and means in said second control valve mechanism operated by said second motor to direct fluid pressure to the first-mentioned control valve mechanism to place the relatively movable valve elements in the first-mentioned relative position.

11. In a hydraulic system; a source of fluid pressure; a reversible fluid motor; a first control valve mechanism between said fluid pressure source and said motor; a second reversible fluid motor; a second control valve mechanism between the first control valve mechanism and said second fluid motor, said first control valve mechanism being operative to direct fluid from said source to the first-mentioned fluid motor to cause a cycle consisting of forward and reverse operation; means operated by said first fluid motor to actuate said first control valve mechanism to interrupt flow from said source to said first fluid motor and establish a flow to said second control valve mechanism; means in said second control valve mechanism for selecting the direction of a succeeding operation of said second fluid motor, said means being operated by said second fluid motor at the termination of the preceding operation thereof; and means in said second control valve mechanism for hydraulically actuating said first control valve mechanism to initiate a cycle of operation of said first fluid motor and interrupt the flow of fluid pressure to said second control valve mechanism.

12. In a hydraulic system, a fluid pressure source; first and second reversible fluid motors; first and second control valve mechanisms, the first control valve mechanism being operative to direct fluid from said source to the first fluid motor to cause a cycle of forward and reverse operation; means operated by said first fluid motor at the termination of reverse operation thereof to actuate said first control mechanism to interrupt fluid flow to the first fluid motor and establish fluid flow to the second fluid motor through the second control mechanism; and means in said second control valve mechanism responsive to the operation of said second fluid motor for redirecting fluid, supplied to said sec-

formed when current flow was interrupted will be completed upon the resumption of current flow. With the hydraulic system shown and described the table and ram cycles cannot be performed out of phase. To prevent the building of pressures which might be injurious to the mechanism during the shifting of valve spools in valve mechanism 75-A, a shunt line 146 has been extended from line 87 to reservoir 17, this shunt line being provided with a pressure relief valve 147.

It will be observed from Figure 5 that the table is provided with a novel work-ejecting mechanism which comprises a slidable pin 148 at each of the work-receiving stages. Such pins are supported for vertical sliding movement and are jointed as at 150 for pivotal movement, such movement being restricted to one direction. As the table moves to the right or left, following a cycle of operation of the ram, the pin 148 moving away from registration with the ram will be moved upwardly by a roller carried by the lower end of the pin moving over a cam surface 151 formed on the support 114. Due to the pivotal movement of the lower portion of the pin 148, the latter will not be moved when the table moves in the opposite direction.

The table 111 is provided with shelf extensions 152 which move under stationary plates 153, as the table moves, the shelf extensions 152 serving to prevent the entrance of foreign material into the space occupied by the motor 110.

While the form of embodiment of the present invention as herein disclosed constitutes a preferred form, it is to be understood that other forms might be adopted, all coming within the scope of the claims which follow.

We claim:

1. In a hydraulic system, a source of fluid pressure; a power cylinder having a ram; valve mechanism between said source and power cylinder to effect the reciprocation of said ram, said valve mechanism having an element responsive to fluid pressure to initiate the operation of said ram; a second power cylinder; a sliding table operated by said second power cylinder; and a second valve means for controlling the operation of said second power cylinder to effect the reciprocation of said table, said second valve means being operative to apply fluid pressure to said pressure responsive element to initiate an operation of said ram.

2. In a hydraulic system, a source of fluid pressure; a fluid motor; valve mechanism between said source and fluid motor, said valve mechanism being automatically operative to cause a cycle of operation of said fluid motor; an element in said valve responsive to fluid pressure to initiate a cycle of operation of said fluid motor; a second fluid motor; a second valve mechanism operative to cause alternate forward and reverse operations of said second fluid motor; and an element in said second valve mechanism actuated by said second fluid motor adjacent the termination of operation in either direction to apply fluid under pressure from said source to the fluid pressure responsive element of said first-mentioned valve mechanism to initiate a cycle of operation of said first-mentioned fluid motor.

3. In a hydraulic system, a source of fluid pressure; a fluid motor; a valve mechanism between said source and said fluid motor; a pair of elements in said valve mechanism operative in certain relative positions to direct fluid from said source to said motor to cause forward and

reverse operation thereof and in another relation to direct fluid from said source to an outlet, one of said elements being actuated by fluid pressure; a second fluid motor; a second valve mechanism connected with said outlet; said second valve mechanism being operative to direct fluid flowing from said outlet to said second motor to cause forward and reverse operation thereof; and a member in said second valve mechanism actuated by said second fluid motor adjacent the termination of operation in either direction to apply fluid flowing from said outlet to the fluid pressure actuated element in said first valve mechanism to initiate a cycle of operation of the first-mentioned fluid motor.

4. In a hydraulic press, a power cylinder; a piston and ram supported for sliding movement in said cylinder; a table disposed for sliding movement to alternately position portions thereof in registration with said ram; mechanism for alternately moving said table and said ram, the latter performing a cycle of pressing and return strokes, said mechanism comprising a source of fluid pressure; a control valve mechanism having a fluid pressure responsive element; a fluid motor connected with said table; a second control valve mechanism for governing the operation of said table; spool valve means in said second control valve mechanism for determining the direction of movement of said table; and a second spool valve element actuated by said table adjacent the termination of movement in either direction to apply fluid pressure to the fluid pressure responsive element of the first-mentioned control valve mechanism.

5. Hydraulic apparatus comprising a frame; a power cylinder supported by said frame; a ram received for sliding movement by said power cylinder; a source of fluid pressure; control valve mechanism between said source and said power cylinder, said mechanism having flow-directing means actuated partly by fluid pressure to cause a cycle of movement of said ram and then direct fluid from said source to an outlet; a second valve mechanism communicating with said outlet; a table supported for reciprocatory movement on said frame; a fluid motor for actuating said table; spool means in said second valve mechanism operative in one position to direct fluid supplied to said second valve mechanism to said table actuating motor to move said table in one direction; and means operated in part by said table adjacent the termination of movement in said direction to move said spool means to a second position to apply fluid supplied to said second valve mechanism to the flow-directing means in said first valve mechanism to initiate a cycle of movement of said ram, the spool means being in position to cause reverse movement of said table at the conclusion of the cycle of movement of said ram.

6. Hydraulic apparatus comprising a power cylinder; a ram disposed for sliding movement in said power cylinder; a fluid pressure source; a valve mechanism between said pressure source and said power cylinder, said valve mechanism having a flow directing element responsive to fluid pressure to initiate the cycles of operation of said ram; a table guided for sliding movement to register certain portions with said ram; a fluid motor for moving said table; valve mechanism for controlling the operation of said table, said last-mentioned valve having a body; a plurality of spool members disposed for movement in said body, said spools cooperating to direct

ond control mechanism, to said first control mechanism to actuate the same to reestablish fluid flow to the first fluid motor and interrupt fluid flow to said second control mechanism.

13. In a hydraulic system, a source of fluid pressure; first and second reversible fluid motors; a first control valve mechanism disposed between said pressure source and the first fluid motor; means in said first control mechanism responsive to fluid pressure to initiate a cycle of forward and reverse operations of said first fluid motor; a second control valve mechanism between said first control mechanism and said second fluid motor; an element in said second control mechanism responsive to fluid pressure to regulate the direction of operation of said second fluid motor; a second element in said second control mechanism, said second element being actuated by said second fluid motor to control the application of fluid pressure to said first-mentioned element; and a third element in said sec-

ond control mechanism operative to direct the entire volume of fluid under pressure flowing to said second control mechanism to the fluid pressure responsive means in said first control mechanism to initiate a cycle of operation of said first fluid motor.
